EIGHT-CHANNEL MEDICAL CONDITION MONITOR

Lambert F. Lyons, 5132 White Oak Ave., Apt. 247,
Los Angeles, Calif. 91316

Filed Dec. 15, 1970, Ser. No. 26,503

Term of patent 7 years

Int. Cl. D24—01

U.S. Cl. D83—1

FIG. 1 is a front isometric view of my invention illustrating the control panel;

FIG. 2 is a top plan view of the medical condition monitor shown in FIG. 1; and

FIG. 3 is a right-side view of the medical condition monitor shown in FIGS. 1 and 2.

The undisclosed rear side of the monitor is plane and unornamented.

I claim:

The ornamental design for an eight-channel medical condition monitor, as shown and described.
